UNITED STATES PATENT OFFICE

MAURICE H. HOFFMAN, OF MINNEAPOLIS, MINNESOTA

DESIGN FOR A COMBINED CASING FOR A CLOCK, FOUNTAIN PEN HOLDER, AND DISPLAY STAND

Application filed June 5, 1931. Serial No. 40,097. Term of patent 3½ years.

To all whom it may concern:

Be it known that I, MAURICE H. HOFFMAN, a citizen of the United States, residing at Minneapolis, in the county of Hennepin and State of Minnesota, have invented a new, original, and ornamental Design for a Combined Casing for a Clock, Fountain Pen Holder, and Display Stand, of which the following is a specification, reference being had to the accompanying drawings, forming part thereof, wherein—

Fig. 1 is a view in front elevation of a combined casing for a clock, fountain pen holder and display stand, showing my new design; and

Fig. 2 is a view in side elevation of the same.

What I claim is:

The ornamental design for a combined casing for a clock, fountain pen holder and display stand substantially as shown.

MAURICE H. HOFFMAN.
